United States Patent

Des. 235,934
Patented July 15, 1975

235,934

TOTE BAG

Maxwell B. Chernoff, Little Silver, N.J., assignor to Dart Industries Inc., Los Angeles, Calif.

Filed Mar. 5, 1974, Ser. No. 448,444

Term of patent 14 years

Int. Cl. D3—02

U.S. CL. D87—3 C

FIG. 1

FIG. 2

FIG. 3

FIG. 4

FIG. 5

FIG. 1 is a front perspective view of a tote bag embodying my new design;

FIG. 2 is a side view (the opposite unseen side is identical) thereof;

FIG. 3 is a front view;

FIG. 4 is a top view thereof; and

FIG. 5 is a bottom view.

I claim:

The ornamental design for a tote bag, substantially as shown.
